UNITED STATES PATENT OFFICE.

LLOYD D. KAY, OF LOS ANGELES, CALIFORNIA.

CAST-METAL WHEEL.

Application filed November 4, 1925. Serial No. 66,738.

This invention relates to cast metal wheels and while the invention may be applied in making cast iron wheels, it is particularly applicable to wheels constructed of electric steel. It is now possible with modern electric furnaces to produce steel which can be cast in walls one-fourth inch thick and even in some cases as thin as three-sixteenths inch.

The general object of this invention is to produce a construction for a cast metal wheel of disk type which will have sufficient strength to support the relatively heavy loads which must be supported by truck wheels, and which at the same time will be of relatively light weight. It is also one of my objects to provide a wheel of this type which, due to its construction, will not develop any internal strains in cooling. In doing this, I avoid the necessity for annealing the wheels constructed in accordance with my invention.

A further object of the invention is to provide an improved construction for the hub and rim of a disk wheel which will operate to prevent the development of internal strains, and as regards the rim, will operate to produce a strong and durable seat for the tire-rim.

Further objects of the invention will appear hereinafter.

The invention consists in the novel parts and combination of parts to be described hereinafter, all of which contribute to produce an efficient cast metal wheel.

A preferred embodiment of the invention is described in the following specification, while the broad scope of the invention is pointed out in the appended claims.

In the drawings:

Figure 1 is a front elevation in partial section through a cast metal wheel embodying my invention, the section being taken about in the plane of line 1—1 of Figure 2.

Figure 2 is a side elevation of the wheel shown in Figure 1 broken away and shown partially in section, the section being taken about in the plane of the line 2—2 of Figure 1.

In practicing my invention I construct the wheel with two walls 1, 1, which I space apart to form the body of the wheel. These walls have outwardly flared extensions 2 at their outer edges, which are preferably curved extensions, see Figure 1; these extensions project laterally and terminate in

cylindrical rim portions 3, the outer faces 3^a of which constitute tire-rim seats.

Around the wheel, the opposite flared portions 2 are united integrally, preferably by bridge members or bridge-webs 4, that is to say, these bridge-webs extend transversely on the face of the wheel and lie substantially in radial planes, see Figure 2.

In order to prevent developing internal strains in the wheel when the cast wheel is cooling, the hub portion 5 of the wheel is preferably not made continuous through the wheel but I form this hub portion by providing two central openings 6 in the walls 1 at this point. At least one of these openings 7 at its edge is provided with a circumferential lip 7 which projects toward the opposite wall. I prefer to provide two such lips 7 which project toward each other but which are not united together, so that a continuous gap 8 is formed extending circumferentially around the hub portion 5 of the wheel.

Where the wheel has a wide face, I prefer to provide a continuous tread-band 9 which is disposed midway between the rim portions 3 and preferably is located in the middle plane of the wheel. This tread-band extends continuously around the wheel and is united integrally with the bridge-webs 4. This band 9 is preferably T-shaped in cross section as also are the bridge-webs.

At a point between the central opening 6 and the rim of the wheel, the walls 1, 1, are integrally connected, preferably by an annular web 10, and this web may be provided with openings 11, which not only lighten the wheel but facilitate the support of the cores when the wheel is being cast.

In order to increase the strength of the rim portion 3 and relieve it of strains from the load carried by the wheel, I prefer to provide a plurality of small ribs 12 which project from the inner edges of the rim portions 3. The outer edges of these ribs are flush with the outer faces 3^a so that they have the effect of increasing the width for the seat of the tire-rim at this point. Furthermore, the inner edges of these ribs are united integrally to the flared or curved portions 2 so that a portion of the weight or load which is carried by the rim is imparted directly to the flared extension of the wheel and this operates to relieve the rim portion 3 of considerable strain.

With a wheel constructed as described it

will be evident that the face of the wheel presents a plurality of large openings 13, that is to say the rim of the wheel is of skeleton form. At the same time it presents an ample seat for the tire-rim. In this way I produce a very light and serviceable cast metal wheel. By reason of the gap 8 in the hub portion 5 of the wheel, it will be evident that when the annular web 11 cools it cannot develop any internal strains in the hub portion 5; at the same time it will be evident that the flared webs 4 in cooling cannot develop any internal strains in the disk walls 1 or in any part of the wheel.

15 It is understood that the embodiment of the invention described herein is only one of the many embodiments this invention may take, and I do not wish to be limited in the practice of the invention, nor in the 20 claims, to the particular embodiment set forth.

What I claim is:—

1. A cast metal wheel of disk type having two walls spaced apart to form the body 25 of the wheel, said walls having outwardly flared extensions at their outer edges projecting laterally and having cylindrical rim portions, the faces of which constitute tire-rim seats, said wheel having transverse 30 bridge-webs uniting the flared extensions at a plurality of points around the wheel, and a continuous tread-band located substantially in the middle plane of the wheel connected to said bridge-webs and constituting 35 a seat for the middle portion of the tire-rim.

2. A cast metal wheel of disk type having two walls spaced apart to form the body 40 of the wheel, each of said walls having a central opening, the edge of at least one of 45 said openings having a lip projecting toward the opposite wall, said walls having outwardly flared extensions at their outer edges projecting laterally and having cylindrical 50 rim portions, the faces of which constitute tire-rim seats, said wheel having transverse bridge-webs uniting the flared extensions at a plurality of points around the wheel, and a continuous tread-band located substantially in the middle plane of the wheel connected to said bridge-webs and constituting a seat for the middle portion of the tire-rim.

3. A cast metal wheel of disk type having 55 two walls spaced apart to form the body of the wheel, each of said walls having a central opening to receive a separate hub or the arm of an axle, the edge of each opening having a lip projecting toward the opposite wall, said walls having outwardly flared extensions at their outer edges projecting laterally and having cylindrical rim 60 portions, the faces of which constitute tire-rim seats, said wheel having transverse bridge-webs uniting the flared extensions at

a plurality of points around the wheel, and a continuous tread-band located substantially in the middle plane of the wheel connected to said bridge-webs and constituting a seat for the middle portion of the tire-rim. 70

4. A cast metal wheel of disk type having two walls spaced apart to form the body of the wheel, each of said walls having a central opening, the edge of at least one of said openings having a lip projecting toward the opposite wall, said walls having outwardly flared extensions at their outer edges projecting laterally and having cylindrical rim portions, the faces of which constitute tire-rim seats, said wheel having transverse 75 bridge-webs uniting the flared extensions at a plurality of points around the wheel, a continuous tread-band located substantially in the middle plane of the wheel connected to said bridge-webs and constituting a seat for the middle portion of the tire-rim, and said wheel further having an annular web 80 extending around the wheel and connecting the side walls at a point between the central openings and the rim of the wheel. 85

5. A cast metal wheel of disk type having two walls spaced apart to form the body of the wheel, each of said walls having a central opening to receive a separate hub or the arm of an axle, said walls having outwardly flared extensions at their outer edges projecting laterally and having cylindrical rim portions, the faces of which constitute tire-rim seats, transverse webs uniting the flared extensions at a plurality of points around the 90 wheel, and an annular web extending around the wheel and connecting the side walls at a point between the central openings and the rim of the wheel. 95

6. A cast metal wheel of disk type having two walls spaced apart to form the body of the wheel, each of said walls having a central opening to receive a separate hub or

the arm of an axle, said walls having outwardly flared extensions at their outer edges 100 projecting laterally and having cylindrical rim portions, the faces of which constitute tire-rim seats, transverse webs uniting the flared extensions at a plurality of points around the wheel, an annular web extending 105 around the wheel and connecting the side walls at a point between the central openings and the rim of the wheel, said wheel further having a plurality of ribs extending from the inner edges of the rim portions 110 toward the middle plane of the wheel, the outer faces of said ribs being substantially flush with the cylindrical faces of the rim portions, and operating to increase the width 115 of support for the tire-rim, and having their inner edges united to the flared extensions so as to impart a portion of the load to the flared extensions and relieve the cylindrical rim portions of a portion of the load. 120

7. A cast metal wheel of disk type having 130

two walls spaced apart to form the body of the wheel, said walls having central openings to receive a separate hub member or the arm of an axle, said walls being unconnected with each other at said openings, and having outwardly flared extensions at their outer edges projecting laterally and having cylindrical rim portions, the faces of which constitute tire-rim seats, said wheel having transverse bridge-webs uniting the flared extensions at a plurality of points around the wheel.

8. A cast metal wheel of disk type having two walls spaced apart to form the body of the wheel, said walls having outwardly flared extensions at their outer edges projecting laterally and having cylindrical rim portions the faces of which constitute tire-rim seats, and integral connecting members uniting the flared extensions around the wheel.

Signed at Los Angeles, California, this 29th day of October, 1925.

LLOYD D. KAY.
